UNITED STATES PATENT OFFICE.

COURTNEY P. WINTER, OF NEW BRUNSWICK, NEW JERSEY.

METHOD OF MAKING PAPER NAPKINS.

1,425,071.

Specification of Letters Patent. Patented Aug. 8, 1922.

Application filed July 8, 1921. Serial No. 483,213.

To all whom it may concern:

Be it known that I, COURTNEY P. WINTER, a citizen of the United States, and resident of New Brunswick, in the county of Middlesex and State of New Jersey, have invented certain new and useful Improvements in Methods of Making Paper Napkins, of which the following is a specification.

10 My invention relates to an improved method of making paper napkins and particularly folded napkins.

Because of their greater convenience, both individually and in packages, folded napkins are considered more desirable and more salable than unfolded napkins. Folded paper napkins have heretofore been produced by machinery and from a roll of paper, but by methods which fail to accumulate the 20 napkins in piles or stacks with sufficient accuracy to insure uniformity and neatness without the expenditure of a prohibited amount of time and labor in straightening out the stacks. It is of great importance in 25 dealing with the article here in discussion to put it on the market in neat packages and it is a primary object of my invention to improve the method of making folded napkins to obviate the difficulty referred to 30 above and to insure stacking of the folded napkins in uniform neat piles.

With this object in view, my invention consists broadly in completing the folding of a web of paper, preferably by machinery, 35 before performing the cutting operations which separate the napkins one from the other. By proceeding in this manner, the web of paper is maintained in a unitary state until all of the folding is completed 40 and the pile of napkins is formed; and by reason of the continuity of the web during the folding and piling operations, the unsevered napkins mutually support and align one another so as to render possible the formation of a uniform and accurately registered pile or stack. When this stage has been reached, or when the pile has been formed, I separate the napkins by cutting through the whole pile by any suitable 45 means, preferably by means of a paper cutting band saw. The particular manner of folding a web of paper so that napkins of the described character will be produced by simply cutting through the pile, is of course 50 an important feature of my invention; and so far as I am aware it has never heretofore

been proposed to completely fold and pile the napkins before severing the same.

In the accompanying drawings, I have shown by way of illustration, two ways of 60 carrying out my method. In these drawings,

Fig. 1 shows in perspective the folding and piling steps of one manner of carrying out the method;

Fig. 2 shows the cutting step for completing the method started in Fig. 1;

Fig. 3 is a view of a napkin opened out and showing the position of the folds;

Fig. 4 shows in perspective another manner of folding the web; and

Fig. 5 shows the lines upon which the pile of Fig. 4 is cut to form the completed napkins.

Referring to Fig. 1, 1 represents a roll 75 of paper of any suitable character for making paper napkins. According to my method this roll of paper is continuously unwound and drawn off in the form of a web 2 and continuously folded by any suitable 80 folding means along its longitudinal median as at 3. This first longitudinal fold comprises for the entire series of napkins formed from the roll 1, the first fold of the so-called square or double fold (see Fig. 3). 85 By any suitable means well known in the art, the longitudinally folded web is then subjected to zig-zag folding to form a pile of superimposed unsevered napkins, having double or 4-ply folds 4, 5 at two opposite 85 sides of the pile, single or 2-ply folds 6 at one side of the pile and free edges along the fourth side of the pile. If desired or necessary the pile may be compacted by any suitable means as shown in Fig. 2.

It will be readily understood that the pile such as has just been described can be converted into two piles of square folded napkins by means of a single cut through the entire pile on the line 7—7 of Fig. 2. A 100 square folded napkin is characterized by one double or 4-ply edge, which corresponds to the folds 4, 5 of Fig. 1; two superimposed single or 2-ply folds along another edge, which corresponds to two adjacent folds 6; the two remaining sides of the napkin comprising four superimposed unfolded edges, as will obviously be produced by cutting the pile in Fig. 1 in the manner indicated in Fig. 2.

In Fig. 4 I have shown another manner of carrying out my method which consists

in forming a double longitudinal fold at 8 and 9, the edges 10 of the web being folded over on the longitudinal median of the web. Preferably a small interval is left between 5 the edges 10 to allow for the width of the cut hereinafter referred to. This longitudinally folded web is then transversely folded in the zig-zag manner as hereinbefore described in connection with Fig. 1 and 10 a pile of superimposed unsevered napkins formed substantially as before described. In the pile formed as in Fig. 4 however, there are on two opposite faces (of which 11 is one) a series of superimposed double 15 or 4-ply folds, broken however at the middle by reason of the free edges 10. In this instance there are single or 2-ply folds on both of the remaining sides of the pile.

In Fig. 5 a top view of the pile is shown 20 and the lines 12-12, 13-13 indicate the cuts which will be given to the pile formed as shown in Fig. 4. When so cut, four piles of napkins (14, 15, 16, 17) will be formed and these napkins will have precisely 25 the same form and will be folded in the same manner as the napkins formed as in Figs. 1 and 2 and illustrated in Fig. 3. By means of this last described manner of carrying out my invention, twice as many 30 napkins can be made simultaneously and of the same dimensions by employing a web of paper twice as wide as that shown in Fig. 1.

By reason of the fact that all of the folding operations are completed before 35 the napkins are severed, I am enabled to maintain absolute control of the web of paper until the pile is completed, thus insuring a smooth and uniform registration of the superimposed napkins. Much neater 40 packages can be economically made from napkins formed by my method and the step of severing the napkins is much simplified according to my method as compared with old methods in which a separate cut is required to sever each pair of napkins and the piling and part of the folding operations are performed after the severing of the napkins.

I claim:

1. The method of making paper napkins which comprises folding a web of paper longitudinally, zig-zag folding said longitudinally folded web to form a pile, and cutting through the pile on the median 55 transverse to the web.

2. The method of making paper napkins which comprises folding a web of paper longitudinally to bring its longitudinal edges in substantial alignment with 60 the longitudinal median of the web, zig-zag folding the web to form a pile, and cutting the pile along its two perpendicular medians.

COURTNEY P. WINTER.
